MOVABLE REFLECTING TOY

Heel L. Bowditch, Jamaica Plain, Mass., assignor
to Bola Toys Incorporated, Greenwich, Conn.,
a corporation of Connecticut

Application May 31, 1947, Serial No. 751,539

18 Claims. (Cl. 46—45)

1

This invention in the illustrative embodiment herein shown provides a novel, inexpensive toy which operates to cast a moving reflection upon ceiling or wall, which may be manipulated in such manner as to constitute an amusing game.

In its broader aspects, however, it relates to mechanism for producing motion and more particularly to mechanism for producing any combination or degree of gyration and oscillation of an axis about a geometric point.

One of the objects of the invention is to impart, by application of force, pivotal motion to an axis, and by changing the direction of application of the force to impart oscillating and gyrating motion components to the pivotal motion. Another object is to cause said axis to move at a controlled speed.

Another object is to provide a light-projecting device operated by motion of the axis for producing on an irregular reflecting surface a visible image which appears effortlessly to move therewith in any direction. Another object is to provide for manual control of the direction and automatic control of the speed of motion of the image.

Other objects will be in part obvious and in part pointed out hereinafter.

In the drawings in which corresponding numerals refer to corresponding parts throughout:

Figure 1 shows in perspective, and more or less diagrammatically, how an embodiment of the invention shaped as an airplane silhouette may be used to project a movable image of an airplane on a ceiling, the light source being sun rays entering a window;

Figure 2 is a perspective view of the toy of Figure 1;

Figure 3 shows the airplane silhouette turned through 180°;

Figure 4 is a longitudinal and axial section taken on line 4—4 of Figure 2;

Figure 5 is an enlarged detailed section taken through the supporting ball and socket of the device of Figure 2;

Figure 6 shows a modification of a light-projecting device used in the toy of Figure 2;

Figure 7 shows another embodiment of the device for supporting and retarding the motion of the silhouette;

Figure 8 shows another embodiment of the invention for retarding the motion of the axis;

Figure 9 shows another embodiment of the invention wherein a spring is used to apply the motion-producing force;

2

Figure 10 shows another embodiment of the invention in which a magnetic field is used as the motion-producing force, and is shown applied to the Figure 7 embodiment;

Figure 11 shows another embodiment of the invention in which universal motion of the image motion-producing axis is obtained by mounting the axis on a three-point support, each point being movable in controlled relationship to the motion of the other points, the speed of motion being controlled by restricting liquid flow; and

Figure 12 is a detail of the valve arrangement used in the device of Figure 11.

Referring to Figure 1, a light-reflecting silhouette 10 in the shape of a plan view of an airplane reflects sunlight (indicated by beam 12) coming through window 13, and projects the reflected rays 17 upon an irregular reflecting surface of ceiling 15 to form airplane image 16, having the shape of silhouette 10. Image 16 is caused to fly on ceiling 15 or on walls 18, the flight being controlled by tilting silhouette 10 to change the angle of incidence between beam 12 and silhouette 10. To this end, silhouette 10 is mounted so that its nose may be tilted up or down, and its wings may be dipped to one side or the other to give image 16 the appearance of flying. Referring to Figures 2 and 5, this silhouette is mounted on a spindle 11 about which the silhouette is rotatable in a plane perpendicular to the spindle axis 11. The spindle 11a, holding the silhouette, is so mounted as to be capable itself of rocking in all directions with respect to the vertical. Thus the miniature airplane may be tipped in any desired direction, so as to produce motion of the reflected image 16 that simulates an airplane flying in the sky. To accomplish this motion a weight, such as shown at 34, is positioned at the front end of the silhouette, thus providing a constant force which tends always to tip the nose of the silhouette downwardly. As will be more fully explained hereinafter, means are provided to retard the tipping movement of the silhouette, and so to retard the rate at which silhouette 10 tilts, and the rate at which image 16 moves, thus creating the illusion of a flying plane.

To obtain the effect of steering the moving image 16, silhouette 10 may be turned about axis 11, and as the silhouette is so turned, the weight, of course, turns with it and so continually tends to tip the nose of the silhouette downwardly, no matter at what degree of azimuth the silhouette points. Thus by manually turning silhouette 10 about axis 11, the direction in which image 16

points is changed, and the plane's image always flies forwardly. The silhouette 10 (Figure 2) is turned about axis 11 by manually turning steering disc 21, which is rotatable through 360°.

The silhouette 10 in the embodiment of Figure 2 comprises a metal stamping having a regular reflecting surface 14. Referring to Figure 4, the stamping and its supporting spindle 11a are supported upon upright post 20 secured to a base 19. Rotatable about post 20 is the steering disc 21 carrying steering pin 22, passing through a slot 23 in plane 10. Rotation of steering disc 21 about post 20 moves pin 22 and rotates plane 10 to change the degree of azimuth at which the plane points. Figure 2 shows the plane pointing to the left; whereas Figure 3 shows it turned through 180°.

Referring to Figure 5, spindle 11a supporting plane 10 extends upwardly from a movable base 24. Plane 10 carries bushing 27 which receives spindle 11a, holds the plane normal to axis 11, and facilitates free turning of the plane about axis 11. Bushing 27 is staked to plane 10 and, as shown in Figure 5, the lower end of the bushing is turned over as at 27a to provide a thrust bearing which runs on surface 26 of base 24.

Bushing 27 passes centrally through the body of the silhouette 10, so that turning of silhouette 10 about spindle 11a merely turns image 16 on the ceiling to change the direction of its flight, and does not give the impression of an unnatural or violent movement of the plane.

The outer annular surface of bushing 27 receives a removable colored transparent disc 29 which rests on top of surface 14 and serves to give the central part of image 16 an identifying color. The disc 29 is removable so that it may be replaced by discs of other colors.

Referring to Figure 5, the mechanism by which spindle 11a is mounted to move plane 10 to give image 16 realistic flight travel will be described. Base 24 has a lower hemispherically shaped part 25, which sets in a spherically shaped cup 30 in the top of post 20. This construction provides for all directions and angles of rocking movement of base 24 in cup 30, and so of plane 10 which, as above described, is supported on the base. Thus the flying image may be guided and positioned as desired.

The plane-supporting base 24 is floated in cup 30 upon a pool of viscous liquid 31 that provides a fluid-friction-retarding force on base 24, that is the liquid provides viscous damping of the movement of base 24. The liquid permits only slow rocking of base 24 in the cup under the influence of weight 34, and resists any tendency of base 24 to rotate about a vertical axis as the silhouette is rotated to guide the flying image. Also, the fluid-friction action of fluid 31 holds the plane in any position of lateral tipping (wing dip) in which it may be while permitting continuous downward tipping of the nose. The liquid 31 may be a material such as heavy grease, or preferably a polymerized hydrocarbon of a straight-chain structure, such as Vistanex #8, sold by Advance Solvents and Chemical Corporation, 245 Fifth Avenue, New York, New York. A viscous material which does not change its viscosity appreciably in temperature ranges from 60-130° F. is preferable.

Movement of base 24 in cup 30 (referring to Figures 2 and 4) is caused by weight 34, which in effect applies to axis 11 a force component normal to the axis causing it to rock base 24 in the direction of the weight. Weight 34 is in

fact a nut which threads on a nose portion 32 extending forwardly from the plane and having opposing serrated edges 33 cut to provide male threads for the nut 34. Nut 34 always overbalances the weight of the tail portion of the plane, but as the nut is moved forwardly on the nose, its leverage to rock base 24 is increased and the plane will tilt faster, thus making the image fly faster over the ceiling.

Movement of base 24 by weight 34, therefore, causes axis 11 to move with respect to a vertical axis X—X. The movement is such as continuously to change the angular position of axis 11 with respect to the vertical axis X—X.

Since axis 11 can rock in any direction about its effective pivot point, any desired angle of incidence is obtainable within the limits of motion of the plane, and the plane silhouette may project the image 16 to any part of the room. In the Figure 2 embodiment, the plane silhouette can be tilted 30° in any direction from the horizontal.

Reviewing the functioning of the parts: since axis 11 is always rocked in a direction determined by the azimuth position of weight 34 about vertical axis X—X, manually changing the position of weight 34 changes the direction of flight of image 16 as desired. Thus, by merely turning steering disc 21, which through pin 22 turns silhouette 10 on spindle 11a, the direction of travel of the image on the ceiling may be changed at will. Because liquid 31 so tightly holds base 24, turning of plane 10 on spindle 11a does not move base 24 and does not cause any motion of image 16 other than to change its direction of flight.

The radius of cup 30 is preferably larger than that of spherical surface 25 of base 24, so that cup 30 acts as a reservoir to hold viscous material 31 between cup 30 and base 24. Spherical surface 25, in effect, floats in the viscous liquid, and as the surface rocks in the liquid, the liquid keeps the surface coated, but the rim of cup 30 extending outwardly from surface 25 does not wipe the liquid from the surface, and so the liquid does not flow from the cup down the sides of post 20.

Annular lip 24a serves to prevent the viscous, sticky, liquid 31 from flowing onto surface 26, and so prevents the liquid from interfering with free turning of plane 10 about spindle 11a. But if material interfering with free turning of plane 10 does get onto bushing 27 or onto surface 26, then the parts are cleaned by lifting plane 10 off spindle 11a.

Referring to Figure 5, base 24 is so constructed that in supporting plane 10 it holds the geometric center of plane 10 approximately at the point A approximately at the center of hemispherical surface 25. To this end, supporting surface 26 and axis 11 are made to intersect approximately at point A. Because of the spherical conformation of part 25, rocking of base 24 in cup 30 does not laterally shift the point A of base 24. Therefore, since the point A, about which the base 24 must rock is centrally located with respect to the wings, and since weight 34 is symmetrically disposed with respect to the wings, lateral tipping of the plane does not shift the weight of the plane laterally, and so imparts no force to base 24 to rock it sideways in liquid 31. Thus, however the plane 10 is laterally tipped, weight 34 always acts to rock axis 11 forwardly without changing the lateral slope of plane 10, and causes image 16 to fly forwardly without any lateral component of motion.

In addition to the entertainment afforded by

steering image 16 about the ceiling, various games may be played. Thus, with two silhouettes, each operated by an individual, a mock plane battle may be carried out. Or by projecting spots of light to define a course around the ceiling, obstacle races may be carried out. Or a map may be projected onto the ceiling and the planes steered over prescribed courses. Also, various kinds of images may be projected. Thus, silhouette 10 may be in the shape of a bird, boat, car, or animal such as a dog or horse, etc.

To obtain a clear well-defined image, reflecting surface 14 is preferably slightly spherically convex. So shaped, the surface projects a slightly enlarged image, with clearly defined edges, whether formed from an artificial light source, or from sun rays. To the same end, surface 14 may be made concave, but using a concave reflecting surface reverses the image so that the plane-moving force would have to be applied to the tail of the plane rather than to its nose.

Referring to Figure 6, the reflecting silhouette may be a mirror 35 with surface 36 masked with paint to leave the reflecting surface 31 to reflect a desired image. Or a replaceable opaque mask of paper may be used to form the image. In this embodiment, the steering hole 23 is provided as before, and in place of extension 32 a slot 38 is provided with notches 39 to receive adjustable weight 40. Spindle 11a supports bushing 27 as in the Figure 2 embodiment.

Referring now to Figure 7, another modification is shown for supporting and rocking axis 11. In this modification, spindle 11a extends from the upper end of a shaft generally indicated at 41, having an upper portion 42 carrying spindle 11a, and a lower portion 44 extending into viscous damping liquid 31. Shaft 41 has an annular groove 45 which is engaged and held by the walls of a hole through a diaphragm 46, made of a thin, highly flexible material such as neoprene or other synthetic rubber-like material.

Liquid 31 is carried in a cup 47 (made of metal or plastic) seated in the top of post 20. Diaphragm 46 is supported from an annular groove 48 in the top inside edge portion of the cup, and is secured therein by crimping, if the cup be metal; or by cementing if the cup be plastic.

The application of force normal to axis 11 causes shaft 41 to rock in any direction about its point of support by diaphragm 46. The viscous liquid 31 by viscous damping retards the rate of the movement as in the Figure 2 embodiment. This construction has the advantage that viscous fluid 31 is, in effect, sealed in cup 47. The shaft 41 may be pulled out of the neoprene diaphragm which, because of its resilient nature, closes over the hole from which the shaft is withdrawn.

The projected image may be steered on the ceiling in the same manner as described in connection with the Figure 2 embodiment. But because the center B about which silhouette 10 pivots on spindle 11a is above the point A about which shaft 41 rocks, when the plane is tilted laterally to dip one wing or the other, center B is moved laterally to one side or the other of the point A, thereby shifting the weight of the plane to one side or other of point A. This imparts to axis 11 a force component normal to the axis, but at right angles to the force component imparted by weight 34, and tends to give the axis 11 a sideward movement in addition to the forward movement imparted by weight 34. The result is that image 16 appears to have a side slip which simulates the sideward movement that a

cross wind imparts to an airplane. This sideward movement makes steering of the airplane on the ceiling more difficult and can be utilized to provide additional interest because of the additional skill required in flying image 16 over the ceiling.

This same effect of producing sideward movement of the plane, in addition to its forward movement, may be obtained in the Figure 2 embodiment by mounting silhouette 10 above the point A about which base 24 rocks.

Referring to Figure 8, another embodiment is shown for supporting spindle 11a about which the plane silhouette 10 turns. In this embodiment spindle 11a is suitably mounted on the end of a circular piece of material 51, supported from base 19. Material 51 is picked for its characteristics which are that of a solid viscous material having low resiliency and bendable slowly under a force applied normal to axis 11 of spindle 11a. Support 51 is shown being bent to the left under the influence of weight 34. Because of the nature of the material, it slowly yields and bends under the influence of the force of the weight and so rocks axis 11 in any direction, as described in connection with the modifications of Figures 2 and 7. The material of support 51 may be polymerized hydrocarbons of straight-chain structure of high molecular weight sold under the trade name "Vistanex" by the above-mentioned Advance Solvents and Chemical Corporation.

The material of support 51 is molded to have a base portion 52 over which an annular clamping support 53 extends to hold base portion 52 on a post 53a suitably secured to and supported from base 19. Post 53a also serves as the shaft for steering disc 21 carrying steering pin 22 as described in connection with Figure 2.

This embodiment has the advantage of simplifying the construction by eliminating liquid material 31 used in the Figures 2 and 7 embodiments. The fact that the center of rotation of silhouette 10 is spaced considerably above the effective pivot point about which spindle 11a moves (namely, the point of connection of material 51 with its base 52), has, in some instances, the effect of producing a side slip in the motion of image 16 on the ceiling as described in connection with Figure 7, and so simulates the kind of slip that a real plane has in flying across the wind.

Referring to Figure 9, in this modification force-applying weight 34 of Figure 2 is replaced by a light spring 54 secured at one end to a post 55 extending upwardly from steering disc 21. Spring 54 at its other end is connected to a rod 57, which extends upwardly from spindle 11a. Post 55 is located diametrically opposite steering post 22 so that the nose of the plane always points at post 55. Thus, the action of spring 54 applies a force to axis 11 in a direction to cause the plane to tilt in the direction of post 55.

If desired, a turnbuckle arrangement (not shown) may be provided to adjust the spring tension of spring 54, and so to provide means for adjusting the speed of movement of image 16 on the ceiling.

Because the pull of spring 54 on rod 57 is always directed toward post 55, when axis 11 is tilted laterally out of the vertical plane containing post 55, the spring pull not only moves the plane nose downwardly, but also acts to reduce the angle between axis 11 and the vertical plane. This action causes the image to fly in a curved course rather than a straight course, and this characteristic may be put to advantage by making more

difficult the steering of image 16 over a desired course, thereby adding to the interest of a game involving skill in flying the image over the ceiling.

Referring to Figure 10, another embodiment of the invention is shown in which a magnetic force is utilized in place of the gravity force supplied by weight 34. In this modification, the lower end 44 of shaft 41 is formed of iron. Magnet 49 having north and south magnetic poles 50, is mounted on steering pin 22, which passes through slot 23 as in the Figure 2 embodiment. The magnet attracts the iron part 44 of shaft 41 and exerts a force upon it pulling it toward the magnet. Plane silhouette 10 is balanced so that its center of gravity is at the point where it passes through axis 11. Thus, pull of magnet 49 on shaft part 44 causes the plane to move in the direction in which the plane is pointed by steering pin 22. By turning the steering disc 21, the direction of the travel of image 16 is changed at will. But because when the plane is tilted laterally, the pull of the magnet on part 44 is not aligned with vertical axis X-X, the force exerted by the magnet tends to give shaft 41 an additional lateral component of motion which adds to the difficulty of steering the plane.

Referring now to Figure 11, in this embodiment spindle 11a is mounted on a post 60 which in turn is secured to a support 61. Support 61 in turn is mounted in such manner as to tilt in any direction. To this end, support 61 is mounted on three legs 62a, 62b and 62c. The points of connection 63 between the legs and support 61 are made flexible. The legs are respectively flexibly secured to pistons 64a, 64b and 64c, operating in piston chambers 65a, 65b and 65c. Piston chambers 65a, 65b and 65c are connected by passages 66a, 66b and 66c to a valve chamber 67 (Figure 12) in which is mounted a rotatable valve 68 having connected passages 69a, 69b and 69c. Valve 68 is rotatable in valve chamber 67 by knob 70 extending above the valve chamber to adjust the alignment of passages 69a, 69b and 69c with passages 66a, 66b and 66c, respectively.

Piston chambers 65a, 65b and 65c, passages 66a, 66b and 66c, and the passages in valve 68 are filled with liquid, and rotational adjustment of the valve 68 varies the freedom of flow of liquid between the piston chambers.

Applying a force normal to axis 11 causes pistons 64a, 64b and 64c to rise and fall, their motion, however, being viscous damped by the controlled flow of liquid from the falling piston or pistons to the rising pistons or piston, thereby tilting axis 11 in the manner described in connection with the Figure 2 embodiment. By adjusting the position of valve 68 by knob 70, the speed of image 16 produced by axis 11 movement is adjustable.

As in the Figure 2 embodiment, an annular steering device 21a is provided carrying steering pin 22, which serves to steer the plane and change the direction of the application of the silhouette-operating force. The operating force may be obtained by gravity as in the Figure 2 embodiment, or by magnet as in the Figure 10 embodiment, or by a spring as in the Figure 9 embodiment.

It is to be understood that in place of a reflecting silhouette 10, the spindle 11a may be enlarged to contain a small battery and lamp that projects a beam of light onto the ceiling, and that by providing a suitable image-controlling film with the lamp, an image may be cast onto the ceiling.

Also in place of the reflecting silhouette a light wood plane (for example balsa wood) may be mounted extending upwardly from the sleeve 27. A rod mounted close to the sleeve 27 would carry the weight 34, and a rod extending in the opposite direction would cooperate with the steering pin to turn the rod carrying the balsa wood plane. Thus the weight 34 would drive the base 24 and the plane, and the steering pin would be used to steer the plane in its flight. The balsa wood plane may be used to cast a moving shadow or may be moved around to simulate the flight of an actual plane.

As many embodiments might be made of the present invention and as many changes might be made in the embodiment disclosed herein, it is to be understood that the foregoing description is to be interpreted as illustrative only and not in a limiting sense.

I claim:

1. In a toy for projecting a moving image upon a ceiling, in combination, a reflecting member for reflecting an incident light beam to form upon an irregular reflecting surface an image, a shaft supporting the member, a rocking support carrying said shaft and permitting rocking motion of the shaft at all angles from the vertical thereby to tilt the reflecting member in all directions and move the image over the ceiling, a force-applying member associated with said reflecting member and disposed to impart rocking motion to the shaft, said force-applying member being movable around said support to change the direction and angle of rocking motion, thereby to change the direction of motion of the image, and damping means associated with said shaft and exerting a retarding force acting against said shaft-rocking motion thereby to regulate the rate of tilting movement of the reflecting member and the speed of image movement.

2. In a toy for projecting a moving image upon a ceiling, in combination, a reflecting member for reflecting an incident light beam to form upon a ceiling an image, a shaft pivotally supporting the member, a rocking support carrying said shaft and permitting rocking motion of the shaft at all angles from the vertical thereby to tilt the reflecting member in all directions and move the image over the ceiling, a force-applying member associated with said reflecting member and disposed to impart rocking motion to the shaft, said force-applying member being movable around said support to change the direction and angle of rocking motion, thereby to change the direction of motion of the image, damping means associated with said support and exerting retarding force acting against said shaft rocking motion thereby to regulate the rate of tilting movement of the reflecting member and the speed of image movement, and mechanism associated with said reflecting member and arranged to turn said reflecting member about the shaft as said force-applying member is moved around the support, whereby as said reflecting member is turned on said shaft to change the direction in which the image points, the force-applying member is simultaneously moved to cause the image to move forwardly in the direction in which it points.

3. In a toy for producing a moving image upon an irregular reflecting surface, in combination, a reflecting member for reflecting an incident light beam to form upon the irregular reflecting surface an image, a rockable support holding

said reflecting member for tilting movement in all directions whereby to move the image over the surface, a force-applying member associated with said reflecting member and disposed to impart a rocking movement to the support, damping means associated with said support for exerting a retarding force against the tilting movement of the reflecting member thereby to regulate the rate of tilting movement and the speed of image movement, and a steering disc operatively associated with said support and reflecting member for changing the position of said force-applying member to change the direction of tilting movement of said reflecting member and so to change the direction of travel of said image.

4. In a toy for producing a moving image, in combination, a light-projecting device for projecting a moving light beam onto an irregular reflecting surface to form a moving image thereon, a rockable support holding said device for tilting movement in all directions to move the light beam over the reflecting surface, force-applying mechanism associated with said device and disposed to impart rocking movement to the rockable support to tip the light-projecting device and move the light beam, a viscous damping device associated with said support for exerting a retarding force against the rocking movement of the support, thereby to regulate the rate of movement and the speed of the light beam, and mechanism associated with said support for changing the position of said force-applying mechanism about said support to change the direction of the rocking movement and so of the travel of the light beam.

5. In a toy for producing a moving light beam on a ceiling, in combination, a light-projecting device for projecting a light beam on said ceiling, a rocking support holding said device for tilting movement in all directions to move the light beam over the ceiling, force-applying mechanism associated with said device and disposed to impart a movement to the light-projecting device and move the light beam, damping means associated with said support for exerting a retarding force against the movement of the light-projecting device, thereby to regulate the rate of movement and the speed of the light beam, and mechanism associated with said support for changing application of said force-applying mechanism about said support to change the direction of the movement of the light-projecting device and so of the travel of the light beam.

6. In a toy for producing a moving image on an irregular light-reflecting surface, in combination, a reflecting member shaped to reflect light and produce an image on the surface, a rockable support holding the member and rockable to tip the member in all directions from the horizontal, thereby to move the image over the surface, a force-applying member associated with said reflecting member and disposed to apply thereto a force to rock the support, a stationary device holding a liquid, said liquid being mechanically interposed between the rockable support and the stationary device to retard rocking movement of the support by applying a viscous damping force thereto to control the speed at which the image moves over the surface, and the direction of application of force exerted by said force-applying member being movable about said rockable support to change its direction of rocking and thereby change the direction of travel of the image.

7. In mechanism for producing an image on

a reflecting surface movable thereacross in a controlled direction and at a controlled speed, in combination, a tilttable image-producing device, a universal mounting supporting said device for universal tilting, force-exerting means associated with said device and disposed to exert a force on said device to tilt said device to cause the image to travel across said reflecting surface, said force-exerting means being movable with respect to said universal mounting to control the direction of tilting of said image-producing device, and said universal mounting including means exerting a retarding force on said image-producing device to control the rate of tilting of said device and thereby the speed at which said beam travels across said reflecting surface.

8. In a device for projecting a moving beam of light onto a reflecting surface, in combination, a light-beam producing member, a movable support therefor having a movable axis, said support being rockable in all directions to move the light beam over the reflecting surface, a force-applying member associated with said support and movable about a vertical axis to apply a force component to said support normal to its movable axis, to rock said support in the direction of said force component thereby to move said light beam in all directions, means mechanically connected to said force-applying member to change its position about said vertical axis, and a flowable liquid associated with said support and adapted to retard movement of said support by viscous damping, thereby to control the speed of movement of said light beam.

9. In a mechanism for producing an image on an irregular reflecting surface, movable thereacross in a controlled direction and at a controlled speed, in combination, an image-producing device, a supporting member having an axis and mechanically holding said image-producing device to maintain its axis fixed with respect to the axis of said support, a mounting mechanism mounting said supporting member and permitting rocking movement of its axis in all directions, a force-exerting device associated with said supporting member to apply a force component thereto to rock said supporting member, thereby to tilt the image-producing device and move the image over the reflecting surface, said force-exerting device being movable around said supporting member to change the direction of the tilting motion and thereby change the direction of movement of the light beam, and fluid-damping mechanism exerting a retarding force on the rocking motion of the supporting member to control the speed of movement of the image over the reflecting surface.

10. In a mechanism for projecting a light beam onto an irregular reflecting surface to cause said light beam to travel thereacross in a controlled direction and at a controlled speed, in combination, a light beam-projecting device, a supporting member having an axis and mechanically holding said light-projecting device to maintain its axis in fixed relation to that of the axis of said support, a mounting mechanism mounting said supporting member and permitting rocking movement of its axis in all directions, a force-exerting device associated with said supporting member to apply thereto a force component to rock said supporting member, thereby to tilt the light-projecting device and move the light beam over the reflecting surface, said force-exerting device being movable around said supporting member to change the direction of the tilting motion and

thereby change the direction of movement of the light beam, and viscous-damping mechanism associated with said mounting mechanism and exerting a force on the rocking motion of the supporting member to control the speed of movement of the light beam over the reflecting surface, said light-projecting device comprising a regular reflecting surface shaped to produce on the irregular reflecting surface an image of a recognizable object.

11. In a mechanism for projecting a light beam onto an irregular reflecting surface to cause said light beam to travel thereacross in a controlled direction and at a controlled speed, in combination, a light beam-projecting device, a supporting member having an axis and mechanically holding said light-projecting device to maintain its axis parallel to the axis of said support, a mounting mechanism mounting said supporting member and permitting rocking movement of its axis in all directions, a force-exerting device associated with said supporting member to apply thereto a force component to rock said supporting member, thereby to tilt the light-beam-projecting device and move the light beam over the reflecting surface, said force-exerting device being movable around said supporting member to change the direction of the tilting motion and thereby change the direction of movement of the light beam, and fluid-damping mechanism associated with said mounting mechanism and exerting a force on the rocking motion of the supporting member to control the speed of movement of the light beam over the reflecting surface, said light-beam-projecting device comprising a regular reflecting surface shaped to produce on the irregular reflecting surface an image of a recognizable object, and said light-projecting device being pivoted on said supporting member to point in the direction of said force component whereby the image moves always in the direction in which it points.

12. In a mechanism for projecting a light beam onto an irregular reflecting surface to cause said light beam to travel thereacross in a controlled direction and at a controlled speed, in combination, a light-beam-projecting device, a supporting member having an axis and mechanically holding said light-projecting device to maintain its axis parallel to the axis of said support, a mounting mechanism mounting said supporting member and permitting rocking movement of its axis in all directions, a force-exerting device associated with said supporting member to apply thereto a force component to rock said supporting member, thereby to tilt the light-beam-projecting device and move the light beam over the reflecting surface, said force-exerting device being movable around said supporting member to change the direction of the tilting motion and thereby change the direction of movement of the light beam, and viscous-damping mechanism associated with said supporting member and adapted to exert a retarding force on the rocking motion of the supporting member to control the speed of movement of the light beam over the reflecting surface, said light-beam-projecting device comprising a regular reflecting surface in the form of a silhouette, and having a slightly convex spherical surface to produce an enlarged and clear reflected image.

13. In a toy for projecting a moving image upon an irregular reflecting surface, in combination, a silhouette having a regular light-refracting surface, a spindle pivotally supporting the sil-

houette and rockable in all directions to tilt the silhouette and thereby move the image over the ceiling, a base having a convex hemispherically-shaped surface, said spindle being carried by and projecting upwardly from said base, a stationary concave socket for receiving the shaped surface of said base, a viscous liquid in the socket to retard rocking movement of the base therein, a weight on one end of said silhouette for over-balancing said silhouette and causing said base to rock in the socket and thereby tilt the silhouette to move the image over the irregular reflecting surface at a controlled speed, and a steering member associated with said silhouette for pivoting the silhouette on the spindle to change the azimuth position of the silhouette to change the direction of movement of the image over the irregular reflecting surface.

14. In a toy for producing a moving image on an irregular reflecting surface, in combination, a light-projecting device for projecting a light beam on said surface, a rockable support holding said device for tilting movement in all directions to move the light beam over the ceiling, said support comprising a flexible diaphragm and a shaft supported from and extending through the diaphragm, force-applying mechanism associated with said support for imparting a rocking movement to the support to tip the light-projecting device and move the light beam, viscous-damping means associated with said support and exerting a retarding force against the rocking movement of the support, thereby to regulate the rate of rocking and the speed of the light beam, said damping means comprising a stationary viscous liquid pool into which said shaft extends, and mechanism associated with said force-applying mechanism for changing the position of said force-applying mechanism about said support to change the direction of the rocking movement and so of the travel of the light beam, and said diaphragm sealing said pool against atmosphere.

15. In a toy for producing a moving image, in combination, an image-producing device for producing an image, a rockable support holding said device for tilting movement in all directions to move the image, said support comprising a shaft of solid flowable non-resilient material anchored at its base, force-applying mechanism associated with said support for imparting a rocking movement to the support to tip the device and move the image, the retarding force of the material of said shaft acting against the rocking movement of the support, thereby to regulate the rate of rocking and the speed of the image, and mechanism associated with said force-applying mechanism for changing the position of said force-applying mechanism about said support to change the direction of the rocking movement and so of the travel of the image.

16. In a toy for producing a moving image on an irregular reflecting surface, in combination, a light-projecting device for producing an image on said surface, a rockable support holding said device for tilting movement in all directions to move the image over the surface, force-applying mechanism associated with said support for imparting a rocking movement to the support to tip the light-projecting device and move the image, said force-applying mechanism comprising a magnet for producing a magnetic field acting on said support, damping means associated with said mechanism adapted to exert a retarding force against the rocking movement of the support, thereby to regulate the rate of rocking and

13

the speed of the image, and mechanism associated with said force-applying mechanism and adapted to change the application of said force-applying mechanism about said support to change the direction of the rocking movement and so of the travel of the image.

17. In a toy for projecting a moving light, in combination, a light-projecting device for projecting a light beam, a rockable support holding said device for tilting movement in all directions to move the light beam, force-applying mechanism associated with said support for imparting a rocking movement to the support to tip the light-projecting device and move the light beam, said force-applying mechanism comprising a spring pulling on said support, viscous-damping means associated with said support and adapted to exert a retarding force against the rocking movement of the support, thereby to control the speed of the light beam, and mechanism associated with said spring for changing the position of said spring about the support to change the direction of the rocking movement.

18. A toy comprising a movable object-simulating device, a universal mounting carrying said device for universal tilting movement, force-ex-

14

erting means forming a part of said device for exerting thereupon a force to tilt said device, said force-exerting means being movable with respect to said universal mounting to control the direction of tilting of said device, and damping means associated with said device and adapted to exert a retarding force on said device to control its rate of tilting and thereby control its speed.
